UNITED STATES PATENT OFFICE.

BRUTUS BROOKS, OF MARTIN, TENNESSEE.

AEROPLANE.

1,078,713.

Specification of Letters Patent. Patented Nov. 18, 1913.

Application filed October 11, 1912. Serial No. 725,334.

To all whom it may concern:

Be it known that I, BRUTUS BROOKS, a citizen of the United States, residing at Martin, in the county of Weakley and State of Tennessee, have invented a new and useful Aeroplane, of which the following is a specification.

This invention relates to aeroplanes and more particularly to means whereby the lateral balance of a machine of this character may be maintained automatically.

A further object is to provide an aeroplane utilizing extension wings in lieu of the usual ailerons, said wings being designed to fold backwardly automatically while the machine is in flight and thus to reduce the surface exposed to the action of the air and, consequently, permitting greater speed than would otherwise be possible.

20 A further object is to provide means whereby the vertical rudder is connected with the balancing devices so as to work in unison therewith.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the machine, a portion of the frame being removed and one of the balancing wings being shown lapped while the other is extended. Fig. 2 is an end view of one of the extended balancing wings. Fig. 3 is an enlarged transverse section through two of the sections of a wing, said sections being shown lapped or telescoped together. Fig. 4 is an enlarged transverse section through a portion of the frame and showing portions of the connections between the balancing wings and the rudder.

50 Referring to the figures by characters of reference 1 designates the sustaining plane of the machine, the same being located at the front end of the skeleton body 2 of said machine. The skeleton body can be of any desired construction and, in the form illus-

trated, is made up of hoops or rings 3 connected by longitudinally extending strips 4 converging rearwardly. A vertical rudder 5 is pivotally connected to the rear portion of the frame 2 and can be of any form desired. The front frame member 6 of the sustaining member 1 is provided, at each end, with a channeled strip 7 to the outer end of which a segment 8 is pivotally connected, the pivot being eccentrically disposed as shown 60 at 9. The two segments have forwardly extending arms 10 to which cables 11 or other flexible devices are secured, said flexible elements being connected to a spring 12 located in front of the center of the frame member 6. Fixedly connected to the outer portion of each segment 10 is a rearwardly extending arm 13 having upper and lower elongated wings 14. Additional arms 15 are pivotally connected to the segments 8, and each 65 of these arms has upper and lower wings 16 similar to the wings 14, each pair of wings converging toward the arms 15 or 13 so that each section made up of an arm and two wings is substantially V-shaped in cross 70 section. Additional arms 17 are pivotally connected to the channeled strips 7 and are provided with upper and lower wings 18 and 19. All of the arms are so arranged as to telescope one into the other and light 75 springs 20 are interposed between and secured at their ends to the arms 13 and 15 respectively while additional similar springs are interposed between and secured to the respective arms 15 and are likewise used for 80 connecting the arms 17, the arms 15 and 17, and for connecting the innermost arms 17 to the ends of the sustaining plane 1. All of 85 these springs are housed between the upper and lower wings 18 and 19.

A lever 20' is fulcrumed within the frame 2 and connected to the upper end of this lever are oppositely extending cables 21 or other flexible devices which are secured at their ends to the respective arms 13. Additional cables or other flexible elements 22 are secured to the lower end of lever 20' and extend in opposite directions therefrom around guide sheaves 23 and rearwardly to the rudder 5, said connections being attached 90 to the rudder at opposite sides of its pivot 24.

It will be apparent that under normal conditions the sections made up of the arms 13, 15 and 17 and the wings thereon are normally extended, as shown at the bottom of 110

Fig. 1, these sections being held apart by the springs 20. Furthermore spring 12 pulling on the connections 11, likewise serves to hold the sections normally extended. These sections remain extended under normal conditions while the machine is in flight. If, however, the machine should tilt laterally, as the result of excessive pressure against one side of the machine, this excessive pressure will cause the extension at the elevated side of the machine to collapse so as thus to reduce the area presented to the air and permit the machine to right itself automatically. As the air pressures upwardly upon the two sides of the machine become equalized, the collapsed balancing wing will gradually be extended until the parts are all restored to their normal position. While the machine is in flight and moving at a high speed, the frictional engagement of the air with the wings 14, 16, and 19 will cause the arms 13, 15, and 17 to swing inwardly thus reducing the area of the sustaining surface and consequently reducing friction and increasing the speed of the machine.

When the machine is to be turned to the right or to the left the rudder is manipulated by means of the lever 20'. When, for example, the machine is to be turned to the left, the rudder is shifted to the position shown in Fig. 1 and this causes one of the connections 21 to pull upon the arm 13 at the right of the machine while the other connection 21 is paid out and becomes slack. Thus the balancing wing at the right side of the sustaining plane 1 is collapsed and the sustaining area at the right or elevated side of the center of the machine is thus reduced so that the machine will not tilt to as great an angle while turning as would otherwise be the case. When the rudder is extended straight backward, both of the connections 21 are taut and both of the balancing wings are extended to a position such as shown at the bottom of Fig. 1.

As will be seen by referring to Fig. 2, the wings, when extended, preferably incline downwardly and rearwardly so as to present a greater angle of incidence than the sustaining plane 1. This results in a greater frictional engagement of the air with the sections of the balancing wings and, consequently, said wings will operate more effectively under the action of the air and will be much more sensitive than would be the case should the angle of incidence of the extension wings be the same as that of the sustaining plane. The springs 20 serve to hold the balancing wings normally extended and with their sections spaced apart equally.

It will be apparent that when either of the wings is collapsed the connections 11-12 serve to pull upon the opposed wing and thus hold it more positively in extended position.

Importance is attached to the particular connection between the rudder and the lever 20' and between said lever and the balancing wings as this arrangement will cause one of the wings to fold when the rudder is shifted out of its normal position.

What is claimed is:—

1. In an aeroplane the combination with a sustaining plane, of interfitting rearwardly extending sections pivotally mounted at their front ends and co-operating to form balancing wings, spring connections between the sections of each wing, and yielding means connecting the wings for holding the wings normally spaced apart and extended to active positions. 80

2. In an aeroplane the combination with a sustaining plane, of balancing wings at the sides of the sustaining plane and each made up of a series of interfitting sections pivotally mounted at their front ends, spring means for holding the wings normally extended, and spring connections between the sections of the wings and completely housed by said sections. 85

3. In an aeroplane the combination with a sustaining plane, of balancing wings at the sides of the sustaining plane, each wing consisting of a group of interfitting rearwardly extending sections pivotally mounted at their front ends, a pivoted member, a second group of interfitting rearwardly extending sections pivotally connected at their front ends to said member, connections between all of the sections of the wings, and spring means for holding the wings normally extended. 95

4. In an aeroplane the combination with a sustaining plane, of balancing wings connected to the sides thereof and made up of interfitting sections normally spread apart, said sections being mounted to nest together when subjected to excessive air resistance. 105

5. An aeroplane including a sustaining plane, an extensible wing at each side thereof, said wing being made up of rearwardly extending sections pivotally mounted at their front ends, spacing devices housed between the sections and adapted to yield to permit the wings to nest when subjected to excessive air resistance. 110

6. In an aeroplane the combination with a sustaining plane, of extensible wings at each side thereof, each wing including interfitting sections and spring means interposed between the sections for holding them normally spread apart, a spring for holding each wing normally extended beyond the sustaining plane, the spacing means between the sections being adapted to permit the wings to fold when subjected to excessive air resistance. 120

7. In an aeroplane the combination with a sustaining plane having a front frame member extending beyond the sides thereof 130

and a segment eccentrically connected to each end of the frame member, of interfitting sections pivotally connected to the frame member and to the segments respectively, spacing springs interposed between the sections for holding them normally apart, said means being adapted to permit the sections to fold together when subjected to excessive air resistance, and a spring for

holding the frame normally extended outwardly beyond the sustaining plane.

In testimony that I claim the foregoing as my own, I have hereto affixed my signature in the presence of two witnesses.

BRUTUS BROOKS.
